SAFETY RAZOR

Frederick C. Rojahn, Brooklyn, N. Y.

Application July 1, 1944, Serial No. 543,095

2 Claims. (Cl. 30—59)

This invention relates to safety razors of the general type in which a thin, flexible, discardable blade is operatively, removably secured between a handled guard plate and blade clamping plate, and has particular reference to improvements in safety razors of this general type in which the blade clamping plate is permanently assembled with the guard plate and the handle against the possibility of loss therefrom and is swingable between blade clamping and blade releasing positions.

Generally speaking, the object of the invention is to provide a safety razor of the type mentioned in which the blade clamping plate is spring biased to blade clamping position and may readily and easily be swung to blade releasing position, and which, at the same time, is of simple, practical construction, of low production cost and thoroughly reliable and efficient in use.

With the foregoing and other objects in view, which will become more fully apparent as the nature of the invention is better understood, the same consists in a safety razor embodying the novel features of construction, combination and arrangement of parts as will be hereinafter more fully described, illustrated in the accompanying drawing and defined in the appended claims.

In the accompanying drawing wherein like characters of reference denote corresponding parts in the different views:

Figure 1 is a front elevation of a safety razor embodying the features of the invention.

Figure 2 is a side elevation of the razor.

Figure 3 is a central, longitudinal, transverse section through the razor showing a blade clamping status of the parts thereof; and

Figure 4 is a view similar to Fig. 3 showing, by dotted and full lines, respectively, partly and fully released positions of the blade clamping plate relative to the guard plate.

Referring to the drawing in detail, it will be observed that the present safety razor is, generally speaking, of conventional design in that it includes, as usual, a guard plate 10 to support a thin, flexible, discardable blade 11, a handle 12 fixed to said guard plate 10 centrally thereof and extending inwardly therefrom at right angles thereto, and a blade clamping plate 13 for operatively clamping the blade 11 against the outer face of the guard plate 10.

The guard plate 10 may be of any suitable design and may be provided along its two opposite longitudinal edges with teeth 14 or with any other suitable means to prevent gouging of the skin by the edges of the blade 11. It may also be pro-

vided with any known or suitable means to hold the blade against superficial movement relative thereto.

The handle 12 is hollow and contains a rod 15 which extends longitudinally with respect thereto, the handle carrying suitable bearings or guides 16 in which said rod is mounted for longitudinal movement and by which it is held against lateral movement relative to said handle.

Arms 17, 17, rigid with the blade clamping plate 13 extend inwardly from the ends, respectively, of said blade clamping plate across the ends of the guard plate 10 and, inwardly of said guard plate, are rigidly connected together by a cross bar 18 which extends transversely relative to the handle 12 through a cam slot 19 cut in the latter.

Rigid with and extending inwardly from the middle of the cross bar 18 is an arm or arms 20 of short length with the inner end or ends of which the outer end of the rod 15 is pivotally connected, as indicated at 21, so that the blade clamping plate 13 may rock or swing laterally relative to said rod 15 as well as with respect to the guard plate 10 and the handle 12.

Between a suitable handle-carried abutment such, for example, as one of the bearings or guides 16, and a suitable abutment carried by the rod 15 such, for example, a cross pin 22 extending through a transverse opening in said rod, is interposed a helical spring 23 which surrounds said rod 15 and is housed by said handle 12 and which tends constantly to urge said rod inwardly and thereby tends constantly to urge the blade clamping plate 13 inwardly to its blade clamping position.

The cam slot 19 is of substantially L-shape and includes an outer end portion 24 which extends longitudinally relative to the handle 12, an inner end portion 25 which extends laterally relative to its outer end portion 24 and an intermediate curved portion 26 by which said outer and inner end portions 24 and 25 are connected and gradually merged with each other.

The outer end portion 24 of the cam slot 19 is substantially equal in width to the thickness of the cross bar 18 and accommodates said cross bar when the blade clamping plate is in its inner or blade clamping position. Thus, said cross bar is held against lateral movement relative to the handle 12 when the blade clamping plate 13 is in its inner or blade clamping and, at the same time, the blade clamping plate is held against swinging movement about the pivotal connection 21 between the rod 15 and the arm 20 due to said rod being held against lateral movement relative to

the handle 12 and to said pivotal connection 21 being disposed outwardly with respect to the cross bar 18. Therefore, when the blade clamping plate 13 is in its inner or blade clamping position it is held effectively in such position against any movement, except outwardly, relative to the guard plate 10.

To the outer end of the rod 15 is secured a cap-piece 27 which covers the outer end of the handle 12 and which is exposed to have finger pressure applied thereto to shift said rod 15 inwardly relative to said handle and thereby shift the blade clamping plate 13 from its blade clamping position to its blade releasing position as shown in Figure 4.

When the rod 15 is shifted inwardly relative to the handle 12 it acts through the arm 20 to shift the cross bar 18 inwardly and to move the blade clamping plate 13 away from the blade 11 and the guard plate 10. At the same time, as the cross bar 18 is moved inwardly from the outer end portion 24 of the cam slot 19, the curved connecting portion 26 of said cam slot cooperates with said cross bar to shift the same laterally relative to the handle 12 into the inner end portion 25 of said cam slot as shown by dotted lines in Fig. 4. However, the cross bar 18 may shift laterally relative to the handle 12 only by swinging about the pivotal connection 21 between its arm 20 and the rod 15 due to said pivotal connection 21 being constrained by said rod to travel only in a straight line longitudinally relative to the handle 12. Manifestly, therefore, when the rod 15 is shifted inwardly the blade clamping plate 13 not only is moved longitudinally of the razor away from the blade 11 and the guard plate 10, but is swung laterally to expose the blade for free and easy removal and replacement. On the other hand, when finger pressure upon the cap piece 27 is relieved, the spring 23 acts to return the parts to their blade clamping positions.

It only is necessary to swing the blade clamping plate 13 through an angle of approximately forty-five degrees, as shown by dotted lines in Fig. 4, to afford all necessary access to the blade 11 for its free and easy removal and replacement, and within said angle of swinging movement of said clamping plate the same is under positive control by the cam slot 19 and the pivot 21. If desired, however, the rod 15 may be shifted inwardly until the cross bar 18 is entirely free of the outer end portion 24 of the cam slot 19, in which event the blade clamping plate 13 is free to swing to a position at substantially right angles to the handle 12 as shown by full lines in Fig. 4. But immediately the rod 15 is released and the spring 23 moves the same the short distance required to cause the cross bar 18 to re-enter the portion 24 of the cam slot 19, return swinging movement of the clamping plate again is under positive control by said cam slot and the pivot 21.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

- 10 1. A safety razor comprising a guard plate to support a blade, a handle fixed to and extending inwardly from said guard plate, a plate to clamp the blade against said guard plate, a bar fixed with respect to and disposed inwardly of said clamp plate and extending transversely relative to said handle, a rod guided for longitudinal movement and held against lateral movement relative to said handle, and a pivotal connection between said rod and said bar whereby said clamp plate is movable outwardly from and inwardly to its blade clamping position by outward and inward longitudinal movements of said rod relative to said handle, respectively, said handle having therein a slot of substantially L-shape in which said bar is disposed and with which said bar cooperates in response to outward movement of said rod to swing said guard plate laterally to blade releasing position and in response to inward movement of said rod to swing said clamp plate laterally to blade clamping position, said slot opening through the side of said handle to permit ready assembly of said bar and said clamp plate as a unit with said handle and said rod.
- 20 2. A safety razor comprising a guard plate to support a blade, a handle fixed to and extending inwardly from said guard plate, a plate to clamp the blade against said guard plate, a bar fixed with respect to and disposed inwardly of said clamp plate and extending transversely relative to said handle, a rod guided for longitudinal movement and held against lateral movement relative to said handle, a pivotal connection between said rod and said bar whereby said clamp plate is movable outwardly from and inwardly to its blade clamping position by outward and inward longitudinal movements of said rod relative to said handle, respectively, said handle having therein a slot of substantially L-shape in which said bar is disposed and with which said bar cooperates in response to outward movement of said rod to swing said guard plate laterally to blade releasing position and in response to inward movement of said rod to swing said clamp plate laterally to blade clamping position, said slot opening through the side of said handle to permit ready assembly of said bar and said clamp plate as a unit with said handle and said bar spring means constantly urging said rod and said clamp plate inwardly, and means for finger engagement to move said rod and said clamp plate outwardly.
- 30 3. A safety razor comprising a guard plate to support a blade, a handle fixed to and extending inwardly from said guard plate, a plate to clamp the blade against said guard plate, a bar fixed with respect to and disposed inwardly of said clamp plate and extending transversely relative to said handle, a rod guided for longitudinal movement and held against lateral movement relative to said handle, a pivotal connection between said rod and said bar whereby said clamp plate is movable outwardly from and inwardly to its blade clamping position by outward and inward longitudinal movements of said rod relative to said handle, respectively, said handle having therein a slot of substantially L-shape in which said bar is disposed and with which said bar cooperates in response to outward movement of said rod to swing said guard plate laterally to blade releasing position and in response to inward movement of said rod to swing said clamp plate laterally to blade clamping position, said slot opening through the side of said handle to permit ready assembly of said bar and said clamp plate as a unit with said handle and said bar spring means constantly urging said rod and said clamp plate inwardly, and means for finger engagement to move said rod and said clamp plate outwardly.
- 40 4. A safety razor comprising a guard plate to support a blade, a handle fixed to and extending inwardly from said guard plate, a plate to clamp the blade against said guard plate, a bar fixed with respect to and disposed inwardly of said clamp plate and extending transversely relative to said handle, a rod guided for longitudinal movement and held against lateral movement relative to said handle, a pivotal connection between said rod and said bar whereby said clamp plate is movable outwardly from and inwardly to its blade clamping position by outward and inward longitudinal movements of said rod relative to said handle, respectively, said handle having therein a slot of substantially L-shape in which said bar is disposed and with which said bar cooperates in response to outward movement of said rod to swing said guard plate laterally to blade releasing position and in response to inward movement of said rod to swing said clamp plate laterally to blade clamping position, said slot opening through the side of said handle to permit ready assembly of said bar and said clamp plate as a unit with said handle and said bar spring means constantly urging said rod and said clamp plate inwardly, and means for finger engagement to move said rod and said clamp plate outwardly.
- 50 5. A safety razor comprising a guard plate to support a blade, a handle fixed to and extending inwardly from said guard plate, a plate to clamp the blade against said guard plate, a bar fixed with respect to and disposed inwardly of said clamp plate and extending transversely relative to said handle, a rod guided for longitudinal movement and held against lateral movement relative to said handle, a pivotal connection between said rod and said bar whereby said clamp plate is movable outwardly from and inwardly to its blade clamping position by outward and inward longitudinal movements of said rod relative to said handle, respectively, said handle having therein a slot of substantially L-shape in which said bar is disposed and with which said bar cooperates in response to outward movement of said rod to swing said guard plate laterally to blade releasing position and in response to inward movement of said rod to swing said clamp plate laterally to blade clamping position, said slot opening through the side of said handle to permit ready assembly of said bar and said clamp plate as a unit with said handle and said bar spring means constantly urging said rod and said clamp plate inwardly, and means for finger engagement to move said rod and said clamp plate outwardly.
- 60 6. A safety razor comprising a guard plate to support a blade, a handle fixed to and extending inwardly from said guard plate, a plate to clamp the blade against said guard plate, a bar fixed with respect to and disposed inwardly of said clamp plate and extending transversely relative to said handle, a rod guided for longitudinal movement and held against lateral movement relative to said handle, a pivotal connection between said rod and said bar whereby said clamp plate is movable outwardly from and inwardly to its blade clamping position by outward and inward longitudinal movements of said rod relative to said handle, respectively, said handle having therein a slot of substantially L-shape in which said bar is disposed and with which said bar cooperates in response to outward movement of said rod to swing said guard plate laterally to blade releasing position and in response to inward movement of said rod to swing said clamp plate laterally to blade clamping position, said slot opening through the side of said handle to permit ready assembly of said bar and said clamp plate as a unit with said handle and said bar spring means constantly urging said rod and said clamp plate inwardly, and means for finger engagement to move said rod and said clamp plate outwardly.
